TWO-WAY COUPLING

Frank A. Reddick, Ranchester, Wyo.

Application September 16, 1938, Serial No. 230,318

4 Claims. (Cl. 285—146)

My invention relates particularly to the art of well drilling. After a well is drilled and the casing is set, the well cylinder contains the back check valve unit and the valved plunger unit is lowered and secured in place by using the drill rod connection to a seating tool. The cylinder is set by rotating the rod in a right hand direction and the rod sections are coupled together by couplings having right hand threads. When, however, it becomes necessary to remove the well cylinder, the drill rod and the tool must be turned in a left hand direction. This has heretofore made it necessary for the well man to provide two complete sets of drill rods, one with right hand 10 couplings to be used in drilling operations and cylinder-setting operations, and the other for use in cylinder-removing operations. It is, therefore, the primary object of my invention to provide a rod coupling by the provision of which only one set of drill rods need be carried by the well repair man to be used both for inserting and for removing or releasing the well cylinder.

Other objects will in part be obvious and in part be pointed out hereinafter.

To the attainment of the aforesaid objects and ends the invention still further resides in the novel details of construction, combination and arrangement of parts, all of which will be first fully described in the following detailed description, and then be particularly pointed out in the appended claims, reference being had to the accompanying drawing, in which:

Figs. 1 and 1^A (readable as one figure by joining lines A—A) constitute a vertical section of a well with the drill rod equipped with my invention in use in setting the cylinder.

Fig. 2 is an enlarged vertical section and part elevation showing my improved coupling assembled for right hand turning to secure the well cylinder in place.

Fig. 3 is a view showing the coupling assembled for left hand turning when removing the well cylinder.

Fig. 4 is a section on the line 4—4 of Fig. 2.

In the drawing, in which like numbers of reference indicate like parts in all the figures, 1 is the well casing, 2 the well cylinder which carries the back check valve unit 3 and the valved plunger 4, and 5 is the seating tool which is designed to engage the well cylinder 2 in any approved way to turn it for the purpose of expanding or contracting the rubber packing 17 to set or release the cylinder accordingly as it is turned in a right hand or a left hand direction.

In applying my invention the tool 5 is welded

at 6 to the lower neck 7 of a female coupling member 8, the lower portion of which is internally threaded as at 10 with a left hand thread.

The member 8 has its upper end provided with an internal right hand thread 9 to receive the right hand threaded bulbous portion 13 of the rod section 12. Below the bulb 13 the rod 12 is threaded at 14 with a left hand thread to enter and fit the thread 10. The thread 9 extends only part way down the member 8 so that the bulb 13 may be screwed past the thread 9 to bring thread 14 into engagement with thread 10 (see Fig. 3).

All rod sections 12 at their ends opposite the bulb 13 are welded to the neck 7 of a female coupling member 8.

When the drill rod is to be used in the ordinary way (right hand turning) a sleeve 16 is inserted in the member 8 to limit the insertion of the bulb 13 to the position shown in Fig. 2, the portion 14 of the rod section 12 lying within the sleeve and the beveled portion 15 engaging with wedging action the sleeve 16. When assembled for left hand turning, the sleeve 16 is left out and the parts coupled as shown in Fig. 3.

It will of course be understood that the lengths of the rod sections 12 (solid rods or tubular rods) may be any length desired, and the number of sections of rods and couplings required will depend on the depth of the well.

By the use of my invention I reduce the number of rod sections which the repair man must carry with him fifty per cent.

From the foregoing description, taken in connection with the accompanying drawing, it is thought that the construction, operation and advantages of the invention will be clear to those skilled in the art to which it relates.

What I claim is:

1. A two-way coupling, comprising a female member having an enlarged bore and a restricted bore, said restricted bore having a left hand thread and said enlarged bore having a right hand thread at its entrant end extending only partly the depth of the enlarged bore, and a male member having at one end a left hand thread to cooperate with the left hand thread of the female member and having a bulbous portion adjacent said one end which bulbous portion has a right hand thread, the construction being such that when the right hand threads of the male and female members are in engagement the left hand threads of the same are not in engagement and vice versa.
2. A two-way coupling, comprising a female

member having an enlarged bore and a restricted bore, said restricted bore having a left hand thread and said enlarged bore having a right hand thread at its entrant end extending only partly the depth of the enlarged bore, a male member having at one end a left hand thread to cooperate with the left hand thread of the female member and having a bulbous portion adjacent said one end which bulbous portion has a right hand thread, the construction being such that when the right hand threads of the male and female members are in engagement the left hand threads of the same are not in engagement and vice versa, and removable means inserted in the female member between its two threaded portions to limit the insertion of the male member into the female member to a position where the right hand threads only engage.

3. In well drill rods, a rod section having one end threaded with a thread of one direction and having adjacent thereto a bulbous enlargement with a thread of the opposite direction, a female coupling member permanently secured to the other end of said rod section and comprising a tubular body having an enlarged bore threaded for a portion only of its length from its outer

end with a thread like that of said bulbous portion and having a reduced bore with a thread like that of the adjacent end of the rod section, the arrangement being such that when the bulbous portion of a rod section is screwed into the female coupling member of another like rod section, the threaded end of the first rod section will be enclosed in the female member without screw contact therewith, for purposes described.

4. In well drill rods, a rod section having one end threaded with a thread of one direction and having adjacent thereto a bulbous enlargement with a thread of the opposite direction, a female coupling member permanently secured to the other end of said rod section and comprising a tubular body having an enlarged bore threaded for a portion only of its length from its outer end with a thread like that of said bulbous portion and having a reduced bore with a thread like that of the opposite end of the rod section for purposes described, and a sleeve to fit into said female coupling member between the threaded parts thereof and having a bore of greater diameter than the outer diameter of said rod section for purposes described.

FRANK A. REDDICK.
